UNITED STATES PATENT OFFICE

LE GRAND L. CLARK, OF BROOKLYN, NEW YORK, ASSIGNOR TO T. W. & C. B. SHERIDAN COMPANY, OF NEW YORK, N. Y., A CORPORATION OF NEW YORK

BOOKMAKING APPARATUS

Application filed June 9, 1927. Serial No. 197,616.

This invention is a novel book making apparatus, referring more especially to the making of headbands for books and to the applying of headbands and back linings to books. The general object of the invention is to afford machinery of the kind referred to which will be of greater efficiency and convenience in operation than heretofore known machines for performing similar operations.

5 10 15 20 25 30 35 40 45 50 55 60 65 70 75 80 85 90 95 100

A particular object is to afford a superior mechanism for attaching headbands to back lining material or paper in preparation for the attachment of the latter to the book; and in this aspect the novel features can be used either to produce a supply of headbanded back lining material to be used at will, or to apply headbands to back lining material immediately in advance of the applying of the latter to the book in the same apparatus. Other and further objects and advantages of the present invention will be pointed out in the hereinafter following description of an illustrative embodiment of the invention or will be apparent to those skilled in the subject.

To the attainment of such objects and advantages the present invention consists in the novel book making apparatus and the novel features of mechanism, combination, arrangement and detail herein illustrated or described.

In the accompanying drawings, which are to some extent diagrammatic in nature, Fig. 1 may be considered an end elevation of an apparatus embodying the present invention, with certain parts shown in section.

Fig. 2 is a top plan view of the apparatus shown in Fig. 1. Fig. 3 is a transverse vertical section taken substantially on the line 3—3 of Fig. 1. Fig. 4 is a similar section taken on the line 4—4 of Fig. 1. Fig. 5 is a perspective view indicating in detail the manner of cutting off and applying to the book a strip of back lining. Fig. 6 in perspective shows a severed strip of back lining material to the ends of which are secured sections of headband.

Referring first to the components of the product or book, B represents the partially completed book, comprising a group of sig-

natures secured together at the lower or back edge and rounded and backed. L is the lining paper drawn from a supply roll, and L' are the edges thereof to which glue has been applied. L² is the lining paper combined with headbands which have been attached to the glued edges, and L³ is the severed strip of headbanded lining paper. H is the headband in its complete form, while H' is the fabric supply from which the strip is drawn for the formation of the headbands. S is the string drawn from a cop to be embodied in the headband. C is the crash or other pervious super material preferably applied to the rounded book back in advance of the lining paper.

The machine comprises frame parts 10 supporting the various mechanisms to be described. A book holding means is shown consisting of a book clamp 11 as appears in Fig. 1. This may for example be one of the successive clamps of a clamp train arranged to travel around a suitable path or orbit preferably with a step by step motion, so that the book pauses in the position shown to receive the back lining strip. The crash lining or super C may have been applied in an analogous manner at an earlier step or stage in the clamp travel.

Upon the base of the machine is shown the standard 12 giving support to the supply roll of the lining paper L. The paper web, which may be of width equal to the length of the book, is shown traveling upwardly beneath a resistance roller 13 which is opposed by two narrow disks 14 arranged at the extreme edges of the web for the purpose of applying stripes of glue. These disks are shown rotating in contact with a glue roll 15 running in a glue vessel 16, a scraper 17 being employed to remove excess glue from the glue disks 14, or to regulate the amount of glue thereon. In referring to glue any liquid adhesive is intended to be included, such as paste, a mixture of glue and paste, or the like.

From the gluing mechanism the web of back lining paper passes upwardly and around a guide roll 18 and thence leftward horizontally toward the position of the book and clamp. Beyond the guide roll 18 is

shown a lower pressure roll 19 and above the traveling material an upper pressure roll 20. As will be described the headband is applied to the glued edges of the web L as it travels 5 from the guide roll 18 to the pressure rolls 19 and 20. The under roll 19 may be the full width of the mechanism, but the upper rolls 20 are preferably short rolls arranged at the edges of the web, and each of them is shown 10 formed with a groove 21 arranged to receive the thickened edge of the headband produced by the interposed string S. The under and upper pressure rolls may be geared together by gearing 22 as seen in Fig. 4.

15 Beyond the pressure rolls is shown a supporting table 23 along which the combined lining paper and headband L' travels to the severing and applying position. Beyond the table 23 is shown a feeding means comprising a lower feed roll 24 and an upper feed roll 25. These rolls are intended to draw the web with headbands along advancingly in an intermittent manner. For this purpose the upper feed roll shaft is provided with a 20 ratchet 26, shown with six teeth, engageable by a pawl 27 pivoted upon a carrier 28 which swings on the feed roll shaft and is connected by a link 29 with a bell crank lever 30, the lower end of which carries a roller engag- 25

30 ing in the groove of a cam 31, this cam also provided with gear teeth engaged by a driving gear 32 preferably turned by power in coordination with the other operations of the machine.

35 It will be seen that each intermittent feed movement throws the headbanded web forwardly beneath the hook B so that it is only necessary to sever a strip of the web, in the form shown in Fig. 6, and bring about a 40 relative movement to apply this to the back of the book, which is assumed to have been provided with a coating of adhesive at a previous stage. The strip severing means may comprise a pair of shearing members, 45 herein illustrated as an upper or fixed knife 33 upon a bracket 34, and a hollow support 35 which constitutes the lower or movable knife, this support rising at a suitable time to cause a shearing action against the upper 50 knife and thus sever the desired strip.

It is advantageous to employ pneumatic means to hold the strip in place until applied to the book. For this purpose the lower knife member or support 35 is shown hollow, 55 with air perforations 36 having their exit at its upper surface. A flexible air connection or hose 37 is shown leading to a suitable pneumatic apparatus. By this means suction may be applied to hold the strip upon 60 the hollow support until applied to the book, when the pressure may be reversed and a puff of air caused to propel or press the strip against the glued back of the book.

The combined pneumatic support and knife 65 35 is shown as movable upwardly and down-

wardly in guides 39. A pair of links 40 may extend from the ends of the support 35 downwardly to a pair of arms 41 mounted on a common shaft, one of these arms being extended downwardly as a bell crank and carrying a roll engaging the groove of a cam 42 rotated from the driving gear 32. By this arrangement the rotation of the driving gear causes the feeding forward of the back lining web, followed by the lifting of the support, which severs a strip and applies it to the book, the support then descending prior to the subsequent feeding operation.

The string or core S for the headband may be supplied in the form of a cop or spool 44 mounted on a supply bracket 45. It is to be understood that there will be a supply of string at each end of the bracket, as indicated in Fig. 2. From each supply the string passes beneath a guide roll 46, and these two guide rolls rotate upon a paste roll 47 revolving in a paste box 48. The string, wet with adhesive, passes forwardly along a guide roll 49, which changes its direction to a longitudinal travel with a downward incline as will be clear from Figs. 1 and 2. In this travel the string passes from the guide roll 49 into position in the fold of the headband fabric H'.

The headband fabric is shown accommodated in a supply box 51 at the upper part of the machine frame, and it may be maintained in the form of a roll or a bolt as shown. The fabric strip passes out by exit 52 of the supply box, one strip issuing at each side of the mechanism. From this point forwardly, each strip is gradually folded over as it approaches a tucker 53. The two tuckers are of a general type known in sewing or other machines and serve to bend double the advancing strip, from which point the doubled strip constituting the headband, and containing the string within its fold, passes directly upon the glued edge L' of the back lining paper web L. The two tuckers are preferably mounted on a fixed bracket 55, the upper part of which carries a cross plate 56 supporting the tucker at each end. Each of the cooperating tuckers comprises the outer shaper 53 and the inner guide 54, the latter being swingably shiftable in a direction contrary to the feeding direction for the purpose of opening the tucker for threading the strip and string therethrough.

By the described arrangement the string and the headband strip are combined into a headband in a substantially continuous manner, this headband being applied to one of the freshly glued edges of the paper web which is to constitute the back lining, the combined web and opposite headbands traveling forward intermittently as drawn by the feed rolls, and presented beneath the book in order to enable a strip thereof, of the proper width, to be severed and applied to the glued back of the book. It will be understood that

at a later stage of the operation on each book a concave or other pressure device will be applied to press the back lining, including the crash C and the paper L with its headbands H snugly to the rounded back of the book.

In a case where the headbanded back lining is to be produced for the purpose of placing in stock to use at will the described severing devices may be dispensed with and the intermittent feed devices replaced by any suitable continuous feed or take-up means, the combined product to be taken up for example in the form of a roll or bolt in readiness to be used subsequently in any back lining machine in the same manner that ordinary back lining paper has been heretofore handled and applied to the books.

As regards certain of the features herein disclosed the headband H could be supplied as a preformed headband to be attached to the back lining web, although preferably the headband is formed as well as applied in the illustrated machine.

Each of the headband tuckers 53 consists of a U-shaped metal piece accommodating the folded fabric and string, with an interior metallic shaping piece 54 pivotally mounted on the bracket 56 in a manner to swing open in a direction contrary to the forward feeding travel, as indicated by the dotted lines in Fig. 2; this permitting the tucker to be opened and the folded fabric and string properly fed and positioned and the shaper 35 swung back into the full line position of Fig. 2.

The relative arrangement of the means for supplying and folding the headband strip H' and the means for supplying the string S thereto is important. The string guide roll 49 is laterally adjacent to the advancing strip near the point where its folding or doubling commences. Owing to this arrangement it will be seen that the string entering the fold 45 of the strip assists in shaping the latter. The string draws closely into the fold and is confined between the tucker and the strip at one side and the inner shaper or guide 54 at the other side. Moreover the paste or glue supplied liberally with the string helps to secure together adhesively the two sides of the folded headband and to maintain them in their folded condition until subsequently applied to the back lining web. The headband material is preferably pervious so that the glue stripe applied to each edge of the web permeates the material of the headband and causes the two layers or folds thereof to adhere over their entire surface. If the adhesive applied to the headband is sufficient in quantity and character it may serve to attach the headband to the web and dispense with the gluing devices 14, 15, 16. Subsequently the glue received from the book will 65 permeate from the other side, and thus the

book, the headband and the back lining will be firmly and strongly consolidated. In the preferred arrangement the headband strip is adhesively moistened before application to the paper web, for example, by the applying 70 to it, by the freely moistened string, of moist adhesive.

Certain well-known details are omitted herefrom as being understood or disclosed in prior patents; for example the upright 75 book clamp combined in a train with other clamps and advanced to bring successive books to position, the pneumatic apparatus for producing first a suction and subsequently a pressure or puff of air beneath the back 80 lining; these and other features have been fully described in certain prior patents of Bredenberg, for example Numbers 1,248,252 and 1,248,254 issued November 27, 1927; and are not herein claimed per se.

There has thus been described a book making apparatus comprising mechanism for making headbands and mechanism for applying the headbands to back lining material and for applying the combined product to 90 books, the same utilizing the principles and attaining the advantages hereinabove recited. Since various matters of mechanism, combination, arrangement and detail may be extensively modified without departing from 95 the principles of the invention it is not intended to limit the invention to such matters except so far as set forth in the appended claims.

What is claimed is:

1. A machine of the class referred to comprising a table for guiding a backlining web flatwise to a position for severance of individual sections thereof, feed means for advancingly drawing a backlining web longitudinally along said table, a guide roll for the web between the supply and said table and arranged with the plane of the table substantially tangent to the guide roll so that the web travels flatwise from the guide roll 105 to the feed means, a device for progressively forming a tape into a headband strip and delivering it to meet the backlining web at a point in line with said table, means for progressively rendering adhesive the margin of 110 the backlining web at a point in advance of the application of the formed headband strip thereon, and means for progressively applying pressure to affix the formed headband strip to the adhesive margin of the backlin- 115 ing web.

2. A machine of the class referred to comprising a table for guiding a backlining web flatwise to a position for severance of individual sections therefrom, means for advancingly drawing a backlining web from a supply and along said table, a guide roll for the web between the supply and said table and arranged with the plane of the table substantially tangent to the guide roll so that the 125 130

web travels flatwise from the guide roll to the feed means, a device for progressively delivering a headband strip to meet the backlining web at a point in line with said table, and means for progressively rendering adhesive one of said components at a point in advance of the meeting point thereof.

3. A machine of the class referred to comprising means for guiding a backlining web flatwise to a position for severance and application to a book, feed rolls between said guiding means and the severing point for advancingly feeding a backlining web from a supply and along said guiding means, a guide roll for the web arranged substantially tangent to the guiding means and delivering thereto, and means for delivering a headband strip to meet the backlining web at a point in line with said guiding means.

20 In testimony whereof, I have affixed my signature hereto.

CERTIFICATE OF CORRECTION.

Patent No. 1,865,557.

July 5, 1932.

LE GRAND L. CLARK.

It is hereby certified that error appears in the printed specification of the above numbered patent requiring correction as follows: Page 3, after line 85, insert the following paragraph-

This application having been in interference with an application of W. C. Schmidt, Serial No. 206,723, filed July 18, 1927, and priority having been awarded to said Schmidt application, this applicant hereby disclaims invention of all subject matter which is disclosed in common by this and said Schmidt applications.;

and that the said Letters Patent should be read with this correction therein that the same may conform to the record of the case in the Patent Office.

Signed and sealed this 1st day of November, A. D. 1932.

(Seal)

M. J. Moore,
Acting Commissioner of Patents.
